PULLEY PACKAGE

William P. Koch, Chicago, Ill., assignor to Chicago Die Casting Manufacturing Company, a corporation of Illinois

Application December 17, 1951, Serial No. 262,070

5 Claims. (Cl. 206—65)

1

The present invention relates to the art of packaging small pulleys each having a hub on one side thereof. Such pulleys are usually enclosed, individually, in small cartons. These cartons are often arranged in little stacks on shelves, counters and elsewhere. A light blow, or a push, against such a stack causes it to collapse, so that the stack must be set up again.

The object of the present invention is to create a simple and novel means for individually packaging such pulleys that when placed in stack formation they automatically interlock and form a stack that is stable.

In carrying out my invention, I employ a container of greater height than the axial length of the pulley and its hub, and provide the same in the top and bottom with openings large enough for the passage therethrough of the pulley hub. Therefore, when a number of the packages are arranged in stack formation, the pulley device within the lowermost container remains housed, while the hub of the pulley in each of the other packages protrudes well down into the next lower container.

Therefore, viewed in one of its aspects, the present invention may be said to have for an object to create a package including a container for a pulley, which occupies no more space than does the container, but from which a part of the pulley device may be caused to protrude and form an interlock with a similar package.

The various features of novelty whereby the present invention is characterized will hereinafter be pointed out with particularity in the claims, but, for a full understanding of the invention and of its objects and advantages, reference may be had to the following detailed description taken in connection with the accompanying drawing, wherein:

Figure 1 is a plan view of a blank for a carton-type container used in the preferred embodiment of my invention; Fig. 2 is a top plan view, on a larger scale, of a package composed of a pulley and a container made from said blank; Fig. 3 is a section on line 3—3 of Fig. 2, showing, however, two packages in stacked formation; Fig. 4 is a section on line 4—4 of Fig. 3; Fig. 5 is a view similar to Fig. 3, illustrating a modified form of container; and Fig. 6 is a plan view of the stack in Fig. 5.

In the drawing 1, 1 represent small pulleys each having on one side a hub 2; the axial length of the hub being a little less than one half of the over all axial length of the whole. This is conventional construction.

2

In the embodiment of my invention shown in Figs. 2-4, these pulleys are packaged, individually, in small square cartons 3, each side of the square being approximately equal to the pulley diameter, and the height of the carton being at least a little greater than the axial length of a pulley and its hub. In this arrangement each carton has in the top a central, round opening 4 slightly larger in diameter than the pulley hub; and there being a similar opening 5 in the bottom of the carton.

When a package is placed on a flat support, indicated by the line A in Fig. 2, the hub of the pulley rests directly on the support, while the upper side of the pulley lies at some distance below the top of the container. When a second package is placed on top of the first one, the pulley in the second package drops down until its hub extends well into the lower container. Thus the two packages are interlocked and will move as a single unit if pushed or pulled laterally.

With containers of the height shown, the hub of the second pulley rests on the lower pulley; but, if a third package is added to the stack, its hub will not reach to the pulley immediately below the same. However, the interlock between consecutive packages remains the same.

The container or carton may be constructed in any suitable way. For example, a very good container may be formed from a cardboard blank such as shown in Fig. 1; the broken lines in this view representing scored fold lines. In the blank 6 and 7 are, respectively, the top and bottom sections of the carton, and 8, 9, 10 and 11 are 35 the four side sections. A flap 12 is joined to one edge of the top section; this flap being glued to section 8 when the blank is folded to create an open-ended shell composed of sections 6, 9, 7 and 8. Each of the sections 8 and 9 has at its ends flaps 14, 15 that are folded inward after the shell 40 has been formed. When side sections 10 and 11 are swung down they hold flaps 14 in place and transform the shell into a carton having six walls. Sections 10 and 11 are provided with flaps 15, 15. 45 When these flaps are tucked in on top of bottom section 7, sections 10 and 11 are locked in carton-closing positions. Flaps 15 are cut away, as indicated at 16, to prevent them from obstructing opening 5, while allowing them to extend far into 50 the carton.

The containers may also be of the cylindrical pill-box type which, as shown in Figs. 5 and 6, is composed of a body member 17 and a cover 18 in the form of a cap frictionally held on the body 55 member. The body member need not have a

3

bottom wall, but may be a simple tube having a marginal portion 19, at the lower end, turned in to provide an annular shoulder that will serve as a rest for the body portion of the pulley when a package is lifted; thereby preventing the pulley from dropping out. The opening 4 in this instance is in the center of the cover 18, so that the packages in stacked formation are interlocked in the same way as is true with the other form.

The containers which I use are no more expensive than conventional cartons which do not form a stable stack. Therefore I am able, at no increased cost, to package pulleys in such a manner that a stack containing two or more packages may be pushed laterally without collapsing.

While I have illustrated and described with particularity only a single preferred form of my invention, together with a single modification, I do not desire to be limited to the exact details thus illustrated and described, but intend to cover all forms and arrangements that come within the definitions of my invention constituting the appended claims.

I claim:

1. A package consisting of a pulley having a hub on one side and a container therefore containing an unobstructed space as wide as the diameter of the pulley and at least as high as the axial length of the pulley and its hub, the container having in the wall facing the hub a central opening smaller in diameter than the pulley and sufficiently large to permit the hub to pass through the same, and there being in the wall, opposite to the aforesaid wall, an opening that has a diameter which also is less than that of the pulley and slightly greater than the diameter of the hub.

2. A package as set forth in claim 1, wherein both openings are of the same size, each having a diameter slightly greater than the diameter of the hub.

3. A package as set forth in claim 1, wherein the container is substantially higher than the

4

axial length of the pulley and its hub so as to allow the hub in the upper of two superimposed packages to extend a substantial distance into the lower container.

4. A package consisting of a pulley having a hub on one side and a square container therefor having flat top and bottom walls, each side of the square being only slightly wider than the diameter of the pulley and at least as high as the axial length of the pulley and its hub, the container having in the top and bottom walls openings smaller in diameter than the pulley and sufficiently large to permit the hub to extend through the same, and the opening in the wall facing the side of the pulley opposite that on which the hub is located being of slightly greater diameter than the hub and of smaller diameter than the pulley; said walls bounding an unobstructed space within which the pulley may move up and down freely so as to be completely housed, along with its hub, or be in a lowered position with the hub projecting below the container.

5. A package consisting of a pulley having a hub on one side and a cylindrical container of the same internal diameter as the diameter of the pulley and of a height greater than the axial length of the pulley and hub, the end of the container facing the opposite side of the pulley from that on which the hub is located being flat and containing a central opening of the same diameter as the hub, and the opposite end of the container being open and having an annular internal shoulder which at times forms a seat for a marginal portion of the pulley.
